UNITED STATES PATENT OFFICE

167,605

FOOD BASKET

Ray Bang, Brainerd, Minn.

Application May 1, 1952, Serial No. 19,558

Term of patent 14 years

(Cl. D58—4)

To all whom it may concern:

Be it known that I, Ray Bang, a citizen of the United States, residing at Brainerd, in the county of Crow Wing and State of Minnesota, have invented a new, original, and ornamental Design for a Food Basket, of which the following is a specification, reference being had to the accompanying drawing, forming part thereof.

Figure 1 is a perspective view of a food basket showing my new design;

Figure 2 is an end elevational view thereof; and

Figure 3 is a plan view thereof showing the basket in unfolded flat position.

The weave effect shown partially in Figures 1 and 2 is continuous throughout the basket, as in Figure 3.

The dominant feature of my design resides in the portion shown in full lines.

I claim:

The ornamental design for a food basket, as shown and described.

RAY BANG.
